CLAIM

The ornamental design for a wireless controller, as shown and described.

DESCRIPTION

FIG. 1 is a perspective view of a wireless controller design showing my new design;

FIG. 2 is an exploded perspective view thereof;

FIG. 3 is another perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

Any shading and cross-hatching are not features of the design but are utilized to illustrate the surface contours of the wireless controller design in the drawings.

1 Claim, 9 Drawing Sheets
